Primary Examiner — Robert M Spear*Assistant Examiner* — Marissa J Cash(74) *Attorney, Agent, or Firm* — Andrew W. Chu; Craft Chu PLLC(57) **CLAIM**

The ornamental design for an airplane with livery, as shown and described.

DESCRIPTION

FIG. 1 is an upper perspective side elevation view of the airplane with livery showing my design with a first patterned surface on the wings, a second patterned surface on the belly, and a third patterned surface on the tail.

FIG. 2 is an opposite side elevation view thereof;

FIG. 3 is an opposite side elevation view thereof;

FIG. 4 is a top plan view thereof;

FIG. 5 is a front elevation view thereof;

FIG. 6 is a bottom plan view thereof; and,

FIG. 7 is a rear elevation view thereof.

Contrasting colors shown by first, second, and third patterned surfaces.

1 Claim, 3 Drawing Sheets(56)
